Primary Examiner—Louis S. Zarfas*Assistant Examiner*—Anhdao Doan(74) *Attorney, Agent, or Firm*—Morgan, Lewis & Bockius LLP(57) **CLAIM**

The ornamental design for a tip for a crutch, as shown and described.

DESCRIPTION

FIG. 1 is a top perspective view of a tip for a crutch in accordance with my new design;

FIG. 2 is a bottom perspective view thereof;

FIG. 3 is a top view thereof;

FIG. 4 is a side view thereof, the other sides being identical to the side shown; and,

FIG. 5 is a bottom view thereof.

The broken lines immediately adjacent the shaded areas represent the bounds of the claim, and all other broken lines are for illustrative purposes only. None of the broken lines form a part of the claimed design.
